United States Patent Office.

AMOS RANK, OF SALEM, OHIO.

Letters Patent No. 96,350, dated November 2, 1869.

HARVESTER.

The Schedule referred to in these Letters Patent and making part of the same.

To all whom it may concern:

Be it known that I, AMOS RANK, of Salem, in the county of Columbiana, and State of Ohio, have invented certain new and useful Improvements in Harvesters, of which the following is a full, clear, and exact description.

The invention herein claimed relates to the devices for discharging the cut grain from the platform in gavels, and constitutes an improvement on the invention shown in Letters Patent of the United States, No. 88,209, granted to me March 23, 1869.

The object of the first part of the invention is so to construct the machine that a rear-delivery or a side-delivery dropper may readily be applied thereto, to which end the improvement consists—

First, of the combination, with the finger-beam, of platform-sections, turning on axes transverse to the finger-beam, supported on brackets connected at their front ends with a rocking-bar, contiguous to and parallel with the finger-beam, and inserted in sockets or lugs on the finger-beam, the brackets extending forward of the bar and under the finger-beam to prevent the sagging of the platform-sections, as herein-after set forth.

The object of the next part of my invention is to dispense with the separating-rod or cut-off used in droppers, and the improvements consist—

Second, of the combination of an oscillating grating on the divider side of the platform, with a series of toothed or slatted overlapping platform-sections, turning on axes transverse to the finger-beam, which sections successively rock in their bearings to discharge the gavel, and then, by a reverse movement, convey the grain which has fallen during this discharge to the divider or grain-side of the platform, and deposit it on an oscillating grating, turning on an axis parallel with that of the platform-sections, from which grating the grain is removed at the commencement of the next discharge.

Third, the improvement further consists of the combination of the vibrating grating with the adjacent platform-section, by means of cranks and a slotted link, which secures their proper relative movements.

The object of the next part of the invention is to preserve the rakes or platform-sections in their proper relation to each other, and the improvement consists—

Fourth, of the combination of oscillating platform-sections, and an oscillating receiving-grating, with a connecting-bar supporting their rear ends.

Fifth, the improvement further consists of a grating or clearing-rake, vibrating on an axis transverse to the finger-beam, and located at the divider or grain-end of the platform.

In the accompanying drawings, all the improvements herein claimed are shown, as embodied in a ma-

chine similar to that shown in my patent of March 23, 1869, hereinbefore mentioned. It will, therefore, be unnecessary here to describe, in detail, the construction of the machine.

Figure 1 represents a plan or top view of my improved machine;

Figure 2, a view, in elevation, of the same, as seen from the rear, with the connecting-bar n^2 broken away;

Figure 3, a similar view of the platform-sections or rakes detached, showing the attitude assumed during their discharge movement;

Figure 4, a side view of the gearing;

Figure 5, a rear elevation of the clearing-rake; and

Figure 6, a vertical transverse section through the finger-beam, at the line $z z$ of fig. 1.

In this instance two driving-wheels, A A', turn loosely on an axle B, with which they are connected by suitable backing-ratchets.

A main frame, C, is mounted in proper bearings on the axle.

The team is attached to a tongue, D, projecting from said frame.

A finger-beam, F, is suspended from the main frame by a drag-bar, E, and coupling-arm E', of well-known construction, and is provided with the well-known Hussey cutting-apparatus.

A bevel-wheel, G, on the main axle, drives a corresponding pinion, h, on a countershaft, h', carrying, on its front end, a wheel, I, having an external spur-pinion, i, on one face, and an internal spur-wheel, i', on the other. The wheel I is held on its shaft by a nut and screw, or equivalent fastening, so that it may readily be removed, reversed, and replaced.

The cutters are operated in the usual way, by a crank and pitman driven by a crank-shaft, J, carrying a small spur-pinion, j.

This pinion, it will be observed, is so arranged as to gear with whichever of the pinions i i' is next to it.

The internally-gearred pinion i' , being larger than the other, of course drives the cutters more rapidly when in gear with the pinion j . This feature, however, forms the subject-matter of an application filed simultaneously with this one, and is not, therefore, herein claimed.

A sprocket-wheel, K, on the main axle, drives, by means of a suitable chain, a corresponding pinion, K', on a shaft, k, mounted in a bracket, C', projecting from the main frame.

A bevel-pinion, k', on the shaft k, drives a corresponding pinion, k'', on a crank-shaft, k''.

A crank, on the shaft k'', reciprocates a slide-bar, L, by means of a pitman, and is thrown into or out of gear by a shifting-lever, L', and a clutch of well-known form.

This slide-bar moves endwise, and parallel to the finger-beam, in suitable guides in the brackets M, which support the platform-sections.

Studs 1, 2, on the slide-bar, act on double wipers n', secured on the platform-sections, which are mounted in brackets M, in a manner similar to that shown in my former patent above mentioned. The studs 1, 2, however, in this instance, are arranged in pairs, one on each side of the wiper, to reverse the movements thereof, as hereinafter mentioned.

Instead, however, of being connected directly with the finger-beam, as in my former patent above mentioned, the shafts N of the oscillating sections are mounted in bearings attached to a rocking-bar, O, to which the brackets M are likewise secured.

This bar is similar in construction to the rocking-bar of the dropper shown in my patent of June 30, 1868, No. 79,500, and is inserted in sockets o o, in the usual well-known way, by which mode of attachment these parts can readily be removed or replaced.

Lugs m, on the brackets, extend forward under the finger-beam, and prevent the dropping of the rear end of the platform-sections. To prevent improper vibration and twisting of the rear end of the sections, they are pivoted to a bar, n².

The front end of an oscillating grating or clearer, R, is mounted in bearings on the divider or grain guard-board Q, while its rear end is supported by the bar n², which is bent up for that purpose.

A link, P, slotted, as shown in fig. 2, is connected at one end to a crank, p, on one of the shafts N.

A crank, r, on the clearer, carries a friction-roller working in the slot r¹.

The operation of the machine is as follows:

The platform-sections, ordinarily, are flat, with their teeth pointing toward the grain side of the machine, as in fig. 1.

When the crank-shaft k² is in gear, the sections N are successively quickly turned over toward the stubble-side of the machine, by the movement of the slide L toward the divider, as in fig. 3, and the gavel is discharged behind the inner drying-wheel.

The movement of these sections is instantly reversed after the discharge of the gavel, and each section, as it turns, clears its predecessor of what little grain has fallen during the discharge-movement. The grain thus accumulated is deposited by the last section on the clearer R.

As this movement takes place, the crank p traverses the slotted link P, over the roller of the crank r, until it enters the enlargement r² in the slot, which causes the clearers to rise and lift the gavel from the last section.

When the crank p has passed its centre, the arm P strikes a pin, n³, on the bar n², which releases the roller from the enlargement of the slot, and the clearer drops, the parts assuming the position shown in fig. 2, in which position the teeth of the platform-section are below those of the clearer.

The sections are stopped by throwing the shaft k²

out of gear, and they remain at rest until the shaft is again thrown into gear, during which time the cut grain continues to fall upon the platform-sections, and the accumulated grain remains upon the clearer.

As soon as the shaft k² comes into gear, the section next the clearer turns over toward the gearing-side of the platform, sweeping the gavel from the clearer, and depositing it on the next section, which in turn deposits on the next one, and so on in succession until the last one, which drops the gavel on the ground. These movements are repeated at each discharge.

It will be observed that the distinguishing peculiarity of my invention is that I first discharge a gavel, then convey the grain which has accumulated during the discharge of the gavel to the divider-side of the platform, deposit it on a grating or clearer, pause until another gavel accumulates on the platform, and then convey the grain on the clearer to the gearing-side, gathering the grain from each section as it goes, and deposit the whole on the ground.

It is obvious that a coupling-device might be attached automatically to stop and start the discharging-apparatus, such, for instance, as segment-gears, and that the details of construction of the devices shown might be varied without departing from the spirit of my invention.

I am aware that oscillating platform-sections have been pivoted on a rocking-bar at their rear ends, so as to lift the front end of the platform-sections away from the finger-beam, and expressly disclaim such construction, as it involves the use of a cut-off, and also the simultaneous lifting of the entire platform, both of which disadvantages are obviated by my improvement.

What I claim as my invention, and desire to secure by Letters Patent, is—

1. The relative arrangement, as set forth, of the finger-beam, the rocking-bar, the platform-sections, connected with the rocking-bar at their front ends only, and the supporting-brackets underlapping but not united to the finger-beam.
2. An oscillating grating or clearer on the divider-side of the platform, in combination with overlapping slatted platform-sections, turning on axes transverse to the finger-beam, as set forth.
3. The combination of a vibrating clearer, with its adjacent platform-section operated by means of cranks and a slotted link, substantially as set forth.
4. The bar n², connecting the rear ends of the platform-sections with the clearer, as set forth.
5. A vibrating grating or cleaning-rake, turning on an axis transverse to the finger-beam, and located at the divider-end of the platform, substantially in the manner described.

In testimony whereof, I have hereunto subscribed my name.

AMOS RANK.
